US0D1003178S

(12) **United States Design Patent** (10) Patent No.: **US D1,003,178 S**
(45) Date of Patent: ** Oct. 31, 2023

(54) **GPS NAVIGATOR**

(71) Applicant: **Bing Liu**, Yichun (CN)

(72) Inventor: **Bing Liu**, Yichun (CN)

(**) Term: **15 Years**

(21) Appl. No.: **29/813,394**

(22) Filed: **Oct. 28, 2021**

(51) LOC (14) Cl. **10-04**

(52) U.S. Cl.

USPC **D10/65**

Primary Examiner — George D. Kirschbaum

Assistant Examiner — Antoinette Martine Suiter

(57) **CLAIM**

The ornamental design for a GPS navigator, as shown and described.

DESCRIPTION

FIG. 1 is a top, front and right side perspective view of GPS navigator, showing my new design;

FIG. 2 is a bottom, rear and left side perspective view;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a bottom plan view thereof; and,

FIG. 8 is a top plan view thereof.

The broken lines in the drawings illustrate the portions of the GPS navigator, which form no part of the claimed design.

1 Claim, 8 Drawing Sheets
